ABSTRACT

A device for slowing an internal combustion engine in the event of oil pressure failure at an engine speed above idle, includes an SCR with the gate thereof connected through a resistor to the field winding of the engine generator. The SCR is connected between an oil pressure sensing switch typically provided for the engine, and the ignition distributor points. Should the oil pressure switch close, indicating low oil pressure, and the engine is turning at sufficient speed so that the generator field provides enough voltage to the SCR gate, the SCR will fire and short the ignition.

FIG_3

FIG_4

OIL PRESSURE FAILURE PROTECTION DEVICE FOR INTERNAL COMBUSTION ENGINES

BACKGROUND OF THE INVENTION

Modern automobiles and trucks are provided with sensors and warning systems which monitor the working functions of the vehicle engine and apprise the operator of serious malfunction. A major operating parameter of an internal combustion engine is the pressure of the lubricating oil, and any disruption of the lubricating system pressure is usually signalled by a dashboard warning light.

In internal combustion engines which are air cooled, and which rely on the lubricating system both for cooling and lubrication, failure of the lubricating system is a catastrophic event. Should the oil pressure fall significantly, and the engine continues in operation, the engine will destroy itself in a matter of a few seconds. The main bearings of the crankshaft will erode, the cylinder walls may be scored, and the engine may seize.

It is an unfortunate yet commonplace aspect of human nature that a vehicle operator who is concentrating on driving may ignore a dashboard light and be totally unaware of an engine malfunction. Should the oil pressure fail at freeway cruising speeds, the driver will barely have time to stop the vehicle before the engine is damaged, even if he or she reacts immediately to the warning light. Clearly, a mere dashboard warning light system is insufficient.

The following United States Patents exemplify the state of the art in devices which react to stop engine operation in the event of oil pressure failure:

3,914,735, 3,116,729, 3,601,103, 2,771,068, 3,362,388, 35
2,445,625, 3,384,062, 2,191,216.

Of these patents, U.S. Pat. No. 2,191,216 relates most directly to the present invention, in that it shows the engine to idle in the event of oil pressure failure, and that it senses idle speed by the voltage generated by the engine generator. However, this prior art system utilizes a solenoid device which must continuously energized, unlike the present invention as detailed in the following.

SUMMARY OF THE INVENTION

The present invention generally comprises a device for sensing the oil pressure of an internal combustion engine, and slowing the engine to idle speed should the oil pressure fall below a predetermined minimum. The invention includes an SCR with one electrode connected through a diode to the oil pressure switch typically provided for the standard oil pressure warning system in a vehicle. The gate of the SCR is connected through a resistor to the field winding of the engine generator. The other electrode of the SCR is connected directly to the ignition distributor points. The voltage from the generator passing across the resistor is sufficient to turn on the SCR only when the engine is turning at a rate above idle speed.

Should the oil pressure fall, the pressure switch will close and ground the one electrode of the SCR. If the generator voltage is sufficient to gate the SCR, the SCR will turn on and connect the distributor points to ground. The engine will immediately stall, slowing until it reaches idle speed. At that point, the generator voltage will be insufficient to operate the SCR gate, and the SCR will turn off. Thus the device will maintain the

engine at idle speed while the oil pressure is low. The pressure warning light, together with the governing action of the device, will notify the driver of the engine malfunction. Further, the limiting of the engine to speed will minimize the damaging effects of the lack of proper lubrication.

THE DRAWING

FIG. 1 is a schematic view of the circuit of one embodiment of the present invention.

FIG. 2 is a schematic view of the circuit of an embodiment of the present invention.

FIG. 3 is a schematic view of a further embodiment of the present invention.

FIG. 4 is a schematic view of the circuit of yet another embodiment of the present invention.

DESCRIPTION OF THE PREFERRED EMBODIMENT

The present invention is generally described as a device for protecting an internal combustion engine from oil pressure failure or other serious or destructive function. As shown in FIG. 1, one embodiment of the invention includes an SCR 11 which has one electrode 12 connected to the distributor points of the engine. The gate of the SCR is connected to a resistor 17, which in turn is connected to the field winding of the generator. The electrode 13 of the SCR is connected to a forward biased diode 14, which is connected in series with a normally open oil pressure sensing switch 18 in the vehicle. It should be noted that the switch 18 has a direct connection to ground when the oil pressure is below a predetermined value.

A dashboard warning light is connected to a voltage source on one side, and to a forward biased diode on the other side. The diode 19 is connected to a normally open switch 18. The resistor 17 serves both to limit the current applied to the gate 16, and to act as a divider to apply only a small portion of the field voltage to the gate. Diode 14 is required to prevent reverse voltage from the indicator light from back biasing the SCR. The diode 19 serves to prevent field voltage above battery voltage levels from actuating the indicator light 21. If the indicator lamp 21 is not provided, diodes 14 and 19 are not required.

The voltage applied to the gate of the SCR is sufficient to fire the SCR only when the engine is turning at nominal cruising speed. Should the oil pressure fall to an unsafe level, the switch 18 will close. The SCR is already fired by the generator field so that the distributor points are connected through the SCR and the switch 18 to ground. The spark plug is thus prevented from firing and the engine stalls.

As the engine slows to a nominal idle speed, the generator field voltage falls until the voltage applied to the gate 16 of the SCR 11 is insufficient to fire the SCR. The SCR turns off and the distributor points are no longer shorted to ground. Thus the engine is limited to idle speed by the invention. It may be appreciated that the value of the resistor 17 determines the speed at which the engine is limited during oil pressure failure, since it controls the amount of the generator voltage applied to the SCR gate.

In the embodiment shown in FIG. 2, the electrodes 11-14 and 16-21 are connected and function in a manner similar to the previous embodiment. The electrode 12 of the SCR is connected to the junction point 24, to which is connected the primary winding 22 and the secondary winding

4
the point 24, as is
the engine is operating at normal speed, the
voltage from the generator field will fire the SCR
which will connect the battery directly through the
circuit breaker and the switch 18 to ground. This short
circuit will cause the circuit breaker to open, thereby
severing the connection between the distributor points
or pump and the battery. The engine will thus stop
immediately. It should be noted that this embodiment
will not reestablish the ignition when the engine slows
below idle speed, as the circuit breaker will remain
open.

10
the SCR will be free of any potential damage from
high voltage, and so that the voltage peaks will not
strike the SCR. If a high voltage SCR is used, the RC
network is not necessary.

15
connected to the ground side of the diode 14 is
a forward biased diode 31, to which a grounding-type
sensor switch 32 is connected. The switch 32
may comprise an engine temperature switch, a fire sen-
t 20
sor like. If the switch 32 is provided with a dash-
indicator light, the light will be connected to the
side of the diode 32. Other switches and indica-
tors may be connected in a like manner. Should any of
thes 25
ches 18, 32, etc., close, and the engine is operat-
ive idle speed, the distributor points will be con-
nected to ground and the engine will be limited to idle
speed before.

25
ould be noted that the protective device of the
n draws virtually no current from the electrical
of the engine when it is operating. It draws
only during an oil pressure failure crisis, an
which occurs infrequently during the life of an
Thus the device conserves energy and fuel,
for art arrangements.

30
embodiment shown in FIG. 3, the elements
16-18 are again employed as before. The
electrode 12 of the SCR is connected to an alarm device
which in turn is connected to positive battery voltage.
Should the switch 18 close and the SCR fire, the
35
switch 18 will be connected to ground and will emit an
signal to warn the operator of engine oil pressure
other malfunction.

35
bodiment depicted in FIG. 4 is designed for
junction with fixed installation internal com-
40
engines such as generating stations or the like.
Electrode 12 of the SCR 11 is connected to the
circuit breaker 36 which is usually provided with such
diesel engines. The circuit breaker is in turn
45
connected to the positive pole of the engine battery.
ected to the electrode 12 is a conductor 37
connected to the ignition circuit of the engine,
to the distributor points (in the case of a spark
ignition), or to the pump of the fuel injection system
of a diesel engine or the like). The circuit
50
13-18 are connected as in the previous em-
bodiment.

55
nection of the gate 16 of the SCR through the
to the generator field permits the engine to
without firing the SCR. Should the switch 18

30

35
1. In combination with an internal combustion engine
having a generator powered electrical system and an
ignition system including breaker points, an engine mal-
function protection device including engine malfunc-
tion sensing means, engine speed limiting means actuated
by said engine malfunction sensing means to limit
the speed of said engine to a predetermined maximum
during the occurrence of a malfunction, and engine
speed sensing means, connected to said engine speed
limiting means, to trigger said speed limiting means
when said engine exceeds a predetermined speed; said
speed limiting means including a solid state switching
device having one electrode connected to said breaker
points, said engine malfunction sensing means including
a normally open switch having one pole connected to
ground and the other pole connected to the other elec-
trode of said solid state switching device, said speed
sensing means including a resistor connected between
the field winding of said generator and the gate of said
solid state switching device.

40
2. The engine malfunction protection device of claim
1, further including a forward biased diode interposed
between said other pole of said switch and said other
electrode of said solid state switching device.

45
3. The engine malfunction protection device of claim
2, further including a series RC network connected
between said one electrode of said solid state switching
device and the low voltage side of said diode.
